(57) **CLAIM**

The ornamental design for a dustpan as shown and described.

DESCRIPTION

FIG. 1 is a front, top, right side perspective view of a dustpan showing my new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

Broken lines shown in the drawings illustrate portions of the dustpan that form no part of the claimed design.
